CLAIM

The ornamental design for a cosmetic tool, as shown and described.

DESCRIPTION

FIG. 1 is a front perspective view of a cosmetic tool showing the new design;

FIG. 2 is a right side view of the cosmetic tool, the left side view being a mirror image thereof;

FIG. 3 is a top view of the cosmetic tool, the bottom view being a mirror image thereof;

FIG. 4 is a front view of the cosmetic tool; and,

FIG. 5 is a rear view of the cosmetic tool.

1 Claim, 5 Drawing Sheets
